UNITED STATES PATENT OFFICE.

JAMES ALEX. JAMIESON, OF MONTREAL, QUEBEC, CANADA, ASSIGNOR OF ONE-FOURTH TO FRANK CAVERHILL AND JOHN B. CAVERHILL, BOTH OF SAME PLACE.

SAFETY APPLIANCE FOR RAILWAY-CARS.

SPECIFICATION forming part of Letters Patent No. 380,630, dated April 3, 1888.

Application filed June 14, 1887. Serial No. 241,304. (No model.) Patented in Canada June 27, 1887, No. 27,072.

To all whom it may concern:

Be it known that I, JAMES ALEXANDER JAMIESON, of the city of Montreal, in the district of Montreal and Province of Quebec, 5 Canada, have invented certain new and useful Improved Safety Appliances for Railway-Cars, (for which I have obtained a patent in Canada, dated June 27, 1887, No. 27,072;) and I do hereby declare that the following is a full, clear, and 10 exact description of the same.

My invention has reference to means for preventing the contents of a railway-car stove or heater from setting fire to the car in any accident, and provides means by which any 15 shifting in position of the heater (as in a collision) or such a disturbance of the equilibrium of the car as would tend to scatter the live coals from the heater (as when a car is turned over) will instantly and automatically 20 extinguish or render innocuous the contents of the stove.

I propose to provide in every car, in close proximity to the heater and connected therewith, a chemical fire-extinguisher the ingredients of which will be kept separate until the 25 occurrence of an accident affecting the car, when they will be automatically caused to mingle, and at the same time the mixture thus made with the gas thereby generated will be 30 forced into the heater and onto the fire.

For full comprehension of the invention reference must be had to the annexed drawings, forming part of this specification, in which—

Figure 1 is a view of part of the inside of a 35 car, showing the heater and extinguisher in position; Fig. 2, a plan view of same; Fig. 3, a transverse sectional elevation taken through cylinder of extinguisher; Fig. 4, a detail, enlarged, of interior of extinguisher; and Fig. 5, 40 detail of valve and locking device.

Similar letters of reference indicate like parts.

A is the heater, of any usual and approved type, such as the "Baker," and B, the fire-extinguisher, to be presently more particularly 45 described. This fire-extinguisher is carried by a bracket, C, secured, preferably, to the end of the car or any transverse partition, on it being pivoted arms C', secured to the cylinder 50 B. It will be seen that unless otherwise supported the extinguisher will fall forward in a direction transversely to the car. From the

heater A projects an arm, A', terminating in a forked end, a; and to the extinguisher B is secured a downwardly-projecting bar, B', with turned-up end b, so arranged that the end b will normally rest in the fork a, and the extinguisher thus be kept in a vertical position and inactive, as will be now explained, so long as nothing happens to the car.

The construction of the extinguisher is as shown in Fig. 4, and now to be described.

D is a bottle or vessel containing such an amount of acid as will, when mixed with the alkaline solution with which B is filled, generate the greatest amount of carbonic-acid gas. E E are downwardly-projecting arms secured to the top of the cylinder B, and serving as bearings for the pivot-pin f of the lever F, carrying on its upper end the seat F', made of or 65 covered with acid-proof material, and on its lower end a weight, G. This bottle D is introduced into the cylinder B through an opening in the top, which opening is secured by a screw-cap, B', preferably carrying on its inside face compression-springs H H, pressing 70 against the bottom of D to keep its mouth closely in contact with the seat F'.

I is the pipe between the extinguisher B and the fire-chamber of the heater A, constructed, preferably, as shown, and I' the outlet from B. The pipe may be either of metal, jointed or flexible, with metal rings around it. K is the valve body or seat, L' being the head of a weighted lever, L, carried on the 85 spindle l on one side of the valve. On this spindle is mounted a disk, M, having its periphery recessed, as shown at m, into which falls, as soon as the weighted lever L has assumed a position which will open the valve, a 90 projection, n, on the free end of a spring, N, secured to the under side of B, or elsewhere, as desired.

The operation of my invention is as follows: The forked end a of the arms A', projecting 95 from the heater, is of such size and so arranged that any ordinary oscillation of the car, even at the highest rate of speed of the train, will not disturb the turned-up end b of the bar B', which holds the cylinder B in a vertical position. So soon, however, whether by the car turning on its side or the heater being shifted from its place from any cause, the turned-up end b is disengaged from the fork a, the ex-

tinguisher B tips over, thus causing the mouth of the bottle D to slide past the seat F', (the springs H H, which offer a yielding resistance, allowing it to do so,) and the acid therein contained is discharged into the alkaline solution contained in the body of B, thus affecting the chemical reaction and the generation of gas. Simultaneously with this movement the head L' of the lever L will leave open the down-pipe I', through which and the pipe I the liquid and gas will be discharged onto the contents of the grate in the heater.

By the operation just described the live coals in the heater will be extinguished or reduced to a condition in which it will be impossible for them to set fire to the wood-work or fittings of the car, and this instantaneously upon any unusual movement of the car or the stove.

From the above it will be seen that without altering in any way the construction of a car I supply means equally applicable to all kinds of cars and independent of any outside supply or mechanism, by which the chances of cars catching fire from derailment or any other accident are reduced to a minimum.

The face of the seat F' may be, if desired, curved, so as to allow it to slip more easily past the mouth of the bottle D.

The fire-extinguisher B may be detached from the wall of the car by withdrawing the pivot-pin connecting the arms C' with the

bracket C, and then used as a portable fire-extinguisher, operated by tipping it.

Having thus described my invention, I beg to state that what I claim is as follows:

1. The combination, with a car-heater, of a chemical fire extinguisher in which the acid-chamber is kept closed by a swinging weighted lever holding a stopper up against its mouth, the said fire-extinguisher being secured to the wall of the car by arms pivoted to it at points outside its vertical axis, a support from the heater holding the extinguisher normally in a vertical position, a pipe connecting the fire-extinguisher with the fire-chamber of heater, and a valve for automatically opening such connection by the tipping of the vessel, all as herein set forth, and for the purposes described.

2. In combination with a car-heater, a chemical fire-extinguisher constructed with arms projecting downward from top, an acid-vessel set inverted in a socket in the top and held between the arms, and a spring pressing it down on a seat carried on the upper end of a weighted swinging lever pivoted on a spindle passing through the arms, all as herein described, and for the purposes set forth.

JAMES ALEX. JAMIESON.
